UNITED STATES PATENT OFFICE.

CHARLES DUCAS, OF NEW YORK, N. Y., ASSIGNOR TO ALEXANDER W. WHITEFORD,
DAVID WALTER PYE, OF NEW YORK, N. Y., AND HIMSELF, AS TRUSTEES.

TENDER TANK.

Application filed April 28, 1927. Serial No. 187,162.

This invention relates to locomotive tender tanks and the like, and more particularly to the bottom constructions thereof.

Heretofore, and as more particularly set forth in my earlier Patent, No. 1,460,710, granted July 3, 1923, the bottom of the tender tank was built up of several sections, the side edges of which were provided with upstanding flanges secured together in overlapping relation. As the result of more or less sudden starting and stopping of the locomotive tender, serious water hammer effects are set up in the tank and unless the latter be strongly constructed, especially the joints thereof, the stresses and strains so occasioned will tend to weaken the tank and spread the joints with injurious results. In an effort to solve this problem, resort has been had to the use of transversely disposed dash-plates in the tank. Owing to the considerable forces exerted on these plates by the fore and aft surging of the water, they need to be secured rigidly in position, and in the arrangement shown in the patent above referred to, these plates are supported by suitable means upon the overlapped flanges extending longitudinally of the tank bottom.

In the present instance the invention contemplates the provision of a bottom unit for the tender tank which is not only simple to construct and assemble but which also includes joints between the several sections of the unit which are of maximum strength and least subject to leakage. In furtherance of this object the invention aims to eliminate the upstanding flanges heretofore employed for securing the several sections of the bottom together, it being contemplated in this instance to weld these sections together. And in place of the intermediately arranged upstanding flanges it is an object of this invention to provide longitudinally extending reinforcing and strengthening ribs, these ribs being in the form of independent members welded in position immediately above and overlying the joints between adjacent sections of the tank bottom.

Other objects of the invention will appear more fully hereinafter.

The invention consists substantially in the construction, combination, location and relative arrangements of parts, all as will be shown in the accompanying drawings, and finally pointed out in the appended claims.

In the accompanying drawings:

Figure 1 is a top plan view of one form of tank bottom construction;

Figure 2 is a transverse section taken on line 2—2 of Figure 1;

Figure 3 is a partial top plan view of a modified form of tank bottom construction;

Figure 4 is a transverse section taken on the line 4—4 of Figure 3;

Figure 5 is a partial top plan view of another modified form of tank bottom construction;

Figure 6 is a transverse section taken on the line 6—6 of Figure 5;

Figure 7 is a partial top plan view of still another construction; and

Figure 8 is a section taken on the line 8—8 of Figure 7.

Referring more particularly to the drawings, it will be seen that the tank bottom 10 may be built up of one or more sections, arranged to lie substantially in a single horizontal plane. In the form shown in Figures 1 and 2 the bottom 10 is composed of three longitudinal sections 11, 11 and 12 provided along their outer edges with upstanding flanges 13. The longitudinally extending side edges of the central section 12 and the portions of the edges of the outer sections 11—11 which are opposite the central section are arranged in abutting relation, as is most clearly shown in Figure 2, in such manner that the meeting edges between the several sections may be butt welded together to form absolutely tight joints. Overlying these welded joints 14 and extending substantially over their entire lengths are a pair of members 15 of substantially inverted T shape, these members being preferably welded in position. A construction of tank bottom such as just described is simple and inexpensive to manufacture at the same time that it is of maximum strength and least liable to leak. Further, the members 15 constitute the necessary longitudinally extending reinforcing and strengthening ribs for the bottom upon which the transversely disposed dash plates (not shown) may be mounted in any suitable manner.

In the modified form of construction shown in Figures 3 and 4 the tank bottom 10 consists of only two sections, 16 and 17, the inner longitudinally extending edges of which are butt welded together as at 18. Inverted T members 19 are provided in the construction shown in Figure 1, but in this modified form

the **T** members are disposed on either side of the welded joint 18 and are welded directly upon the sections 16 and 17. As in the former instance the tank bottom is provided 5 with upstanding flanges 20 along the outer edges thereof.

In Figures 5 and 6 the tank bottom 10 is in the form of a single stamping having the upstanding flange 21 extending around its outer edges. Reinforcing and strengthening 10 ribs are provided in the form of inverted **T** members 22 welded to the tank bottom, these members being spaced laterally from each other and from the side edges of the tank 15 bottom as in the former instances.

Figures 7 and 8 show still another modification of tank bottom construction wherein the joints between the several sections are butt welded together. In this form of construction the longitudinally extending reinforcing and bracing ribs take the form of strips 23 of substantially rectangular cross section, these strips being arranged to lie in substantially vertically extending planes 20 with their bottom edges overlying and forming part of the welded joints 24. As in each 25 of the other forms of construction the outer edges of the tank bottom 10 are provided with upstanding flanges 25.

30 What is claimed as new and useful is:

1. In a locomotive tender tank construction, a bottom therefor comprising a plurality of sections having upstanding flanges along their outer edges, said sections lying substantially in a common horizontal plane such that the inner edges thereof are in abutting relation, welds sealing said abutting edges, and independent upstanding members 35

welded upon and extending longitudinally along said bottom, said members being laterally spaced from each other and from said upstanding outer flanges. 40

2. In a locomotive tender tank construction, a bottom therefor having upstanding flanges around its outer edges and independent upstanding members welded upon and extending longitudinally along said bottom, said members being laterally spaced from each other and from said upstanding outer flanges. 45

3. In a locomotive tender tank construction, a bottom therefor comprising a plurality of sections having upstanding flanges along their outer edges, said sections lying substantially in a common horizontal plane 50 such that the inner edges thereof are in abutting relation, an independent upstanding member extending along said abutting edges and a common weld sealing said abutting edges and securing said independent upstanding member in position. 55

4. In a locomotive tender tank construction, a bottom therefor comprising a plurality of longitudinally extending sections having upstanding flanges along their outer edges, said 60 sections lying substantially in a common horizontal plane such that the inner edges thereof are in abutting relation, independent upstanding members extending longitudinally along said bottom over said abutting edges 65 and welds sealing said abutting edges and securing said independent members to the bottom. 70

In testimony whereof I have hereunto signed my name.

CHARLES DUCAS.
